Primary Examiner — Dana K Weiland*Assistant Examiner* — Kathryn Elizabeth Zieno(74) *Attorney, Agent, or Firm* — Jeffrey Pervanas; Riches, McKenzie & Herbert LLP(57) **CLAIM**

We claim the ornamental design for a rain cap for gas venting system, as shown and described.

DESCRIPTION

FIG. 1 is a front and top perspective view of a rain cap for gas venting system showing the design.

FIG. 2 is a front and bottom perspective view thereof.

FIG. 3 is a top view thereof.

FIG. 4 is a front view thereof.

FIG. 5 is a rear view thereof; and,

FIG. 6 is a bottom view thereof.

1 Claim, 6 Drawing Sheets(56)
